[57] CLAIM

The ornamental design for a combined teabag holder and squeezer, as shown and described.

DESCRIPTION

FIG. 1 is a left perspective view of a combined teabag holder and squeezer showing my new design;

FIG. 2 is a rear elevational view thereof;

FIG. 3 is a left side elevational view thereof, in a closed position;

FIG. 4 is a right perspective view thereof, the cup shown in broken lines for illustrative purposes only.
